UNITED STATES PATENT OFFICE.

FERDINAND ZOGBAUM, OF NEW YORK, N. Y., ASSIGNOR TO WESTERN ELECTRIC COMPANY, INCORPORATED, OF NEW YORK, N. Y., A CORPORATION OF NEW YORK.

SIGNALING SYSTEM.

Application filed January 19, 1922. Serial No. 530,275.

This invention relates to signaling systems, and particularly to such systems in which switches or other objects may be remotely controlled and supervised. The invention is particularly adapted for use in connection with automatic switches or circuit breakers employed with power lines.

It is an object of the invention to provide a system of this character which includes a minimum number of operating elements, and which is reliable and rapid in operation.

It is another object of the invention to provide a remote control and supervisory system embodying a plurality of sequence relays which are operated by a series of positive and negative impulses transmitted over a common control wire and accomplishing the supervision and control of the various devices over a common line wire without the use of selectors or synchronous distributors.

To this end, the invention provides a full relay system comprising a series of polarized relays in pairs, one relay of each pair being located at the control station and the other at the substation. The pairs of relays operate successively under the control of positive and negative impulses supplied over a common wire associating the two stations.

The operation of each pair of relays establishes for an instant a circuit which includes a control wire between the two stations, a key which is set manually or mechanically and a controlling relay. Each switch is adapted to energize a corresponding controlling relay by means of positive or negative current over the control wire depending upon the position in which the switch is set. The controlling relay operates accordingly and controls a circuit for a signaling device at the control station. Certain of the pairs of polarized relays serve to operate the controlling relays at the substation, while others operate the controlling relays at the central control station. The keys at the control station are set manually. The switches at the substation are set mechanically by the devices which are to be finally controlled and their purpose is to control the controlling relays to selectively operate supervisory lamps.

Other objects and advantages of the invention will become apparent from the following detailed description taken in connection with the accompanying drawing which

shows diagrammatically one embodiment of the invention.

Referring to the drawing, the reference letters A and B indicate, respectively, a control station and a substation, the latter being provided with a plurality of power switches 1, 2 and 3, only three such switches being shown for the sake of clearness. In order to indicate whether switches 1, 2 and 3 are open or closed, a number of supervisory lamps are provided at the central station, of which lamps 4 and 5 show the position of power switch 1, lamps 6 and 7 showing the position of power switch 2, and lamps 8 and 9 serving to indicate the position of switch 3. At station A, there are provided a plurality of manually operated keys 11, 12 and 13 which correspond to the power switches 1, 2 and 3, respectively. Connecting stations A and B are a control wire 10 and a line wire 14 which are the only metallic connections between these stations. The power switches 1, 2 and 3 at the station B have associated with them relays 15, 16 and 17, respectively, which may be the ordinary type of polarized relay adapted to control the operating solenoids of their respective power switches. The circuits of the indicating lamps at the station A are adapted to be controlled by similar polarized relays, lamps 4 and 5 being controlled by relay 18, lamps 6 and 7 by relay 19 and lamps 8 and 9 by relay 20. A pair of polarized relays are associated with each power switch to be controlled, one of each such pair being located at station A and the other being located at station B. Such a relay 21 at station A is associated with the power switch 1 and a similar relay 22 is associated with the same switch at station B, while power switch 2 is provided with relays 23 and 24, and switch 3 is provided with relays 25 and 26. These relays are all of the polarized type having two separate windings, as shown in the drawing, and an armature normally held in a centered position by means of suitable springs. One core of each of these relays has a non-freezing ring, such as that shown at 27, while the opposite core is without the non-freezing ring the relays being polarized negatively for purposes hereinafter to be explained. These polarized relays are adapted to be operated successively to control the respective power switches, the lower windings of the relays being operating windings and

the upper windings simply being employed to repel the relay armatures to return them to normal when energized by current of positive polarity after a complete cycle of operations has taken place. Similar pairs of polarized relays are provided, one of each pair at the control station and the other at the remote station, for receiving the answer-back signal and controlling the operation of the lamp-controlling relays. Of these relays, 28 and 29 are associated with power switch 1, while relays 30 and 31 are associated with power switch 2, and relays 32 and 33 are allotted to switch 3. A neutral relay 34 is provided at station A and a similar relay 35 is provided at station B for controlling the flow of current to the line wire 14 and for applying current of positive polarity to the upper windings of the relays just described, as will hereinafter more fully appear. An impulse wheel 36 is adapted to cooperate with a spring pile-up 37 and a suitable source of current to impress alternately positive and negative current impulses on the control wire 10. This wheel is driven continuously at a given rate of speed by an electric motor 38 or other source of power.

The operation of the system is as follows, assuming that the control keys 11, 12 and 13 have been moved to the position shown in the drawing: The rotation of the impulse wheel 36 causes spring pile-up 37 to impress alternately positive and negative current impulses on control wire 10, there being a positive and negative impulse generated for the control of each switch. For a short period at the end of the train of impulses, there is no current on the line wire, when the impulse wheel 36 is in the position shown in the drawing. The first impulse transmitted is negative and operates polarized relays 21 and 22 simultaneously, causing them to attract their armatures, the circuit for relay 21 being traceable from the source of negative current, through spring pile-up 37, conductor 38', contact 39 and lower winding of relay 21 to ground; and the energizing circuit for relay 22 being established from the same source of current, through pile-up 37, control line 10, contact 40 and lower winding of relay 22 to ground. The armatures of relays 21 and 22 on becoming attracted by negative current, closes their contacts 41 and 42, respectively, the relays holding this position throughout the duration of the impulse. This allows current to flow from station A establishing an energizing circuit for power switch controlling relay 15, such circuit extending from battery, through key 11, contact 41 of relay 21, conductors 43 and 44, contact 45 of relay 34, line wire 14, contact 46 of relay 35, conductors 47 and 48, contact 42 of relay 22, windings of relay 15 to ground. The relay 15, being polarized, takes the position cor-

responding to key 11 due to receiving positive or, as in the present case, negative current as determined by the position of the key. The operation of relay 15 opens or closes the remotely controlled power switch 1 in the usual manner. On completion of the first impulse, relays 21 and 22 resume the centered or normal position shown in the drawing. The second impulse, being positive, operates the lower portions of relays 21 and 22 and in the opposite direction, repelling the armatures, leaving contacts 41 and 42 open, opening contacts 39 and 40 and closing contacts 49 and 50, respectively. The opening of contacts 39 and 40 cuts the lower operating windings of relays 21 and 22 from the control wire, the relays remaining in this position since the respective armatures are held against the uppermost core which is not equipped with the non-freezing ring.

By the closing of contacts 49 and 50, the same impulse, which is positive, is now permitted to flow to the lower operating windings of relays 23 and 24 in a direction reverse to the direction of current flow through the lower windings of relays 21 and 22, thereby causing these relays to attract their armatures to their lower pole pieces. The energizing circuit for relay 23 is traceable from battery, through spring pile-up 37, conductor 38', contact 49 of relay 21, conductor 52, contact 53 and lower winding of relay 23, to ground; and the energizing circuit for relay 24 being established from the same source of current, through spring pile-up 37, conductor 10, contact 50 of relay 22, conductor 54, contact 55 and lower winding of relay 24 to ground. The relays 23 and 24 operate simultaneously and in an identical manner with that just described for relays 21 and 22, but in this case, current is allowed to flow from battery at station A through key 12, contact 56 of relay 23, conductors 43 and 44, contact 45 of relay 34, line wire 14, contact 46 of relay 35, conductors 47 and 48, contact 57 of relay 24, windings of relay 16, to ground. The power switch 2 is then operated. The next impulse impressed upon the line by the impulse wheel 36, being negative, again operates relays 23 and 24 in the opposite direction, disconnecting the operating windings of these relays from the control wire 10, and connecting relays 25 and 26 to the control wire and energizes the lower windings of these relays in the manner just described. The operation of relays 25 and 26 is similar to that described in connection with relays 21 and 22.

The operation of relays 28-29, 30-31, and 32-33, controlling the circuits of the indicating lamps is similar to that described for relays 21-22, 23-24 and 25-26, respectively, the circuit for relay 28 being

traceable from source of current, through contact of pile-up 37, conductor 38', contact 49 of relay 21, conductor 52, contact 67 of relay 23, conductor 68, contact 69 of relay 25, conductors 70 and 71, contact 80 of relay 28, lower winding of relay 28, to ground. The circuit for relay 29 at the station B may be traced in a manner similar to that described for relays 22, 24 and 26. On the 10 closing of the contacts corresponding to contact 60 of relay 28, current is permitted to flow from battery at station B through contacts corresponding to auxiliary contact 61 carried by power switch 1, through the conductor, such as 62, contact 63 of relay 29, conductors 64 and 47, contact 46 of relay 35, line conductor 14, contact 45 of relay 34, conductors 44 and 65, contact 60 of relay 28, conductor 66, windings of lamp controlling 15 relay 18, to ground. The relay 18, being polarized, takes the position corresponding to power switch 1 due to receiving positive or negative current, as determined by the position of that particular switch. The 20 same impulse which causes the second operation of relays 32 and 33 operates neutral relays 34 and 35, the energizing circuit for relay 34 being traceable from source of current, through spring pile-up 37, conductor 38', contact 49 of relay 21, conductor 52, contact 67 of relay 23, conductor 68, contact 69 of relay 25, conductors 70 and 71, contact 72 of relay 28, contact 73 of relay 30, contact 74 of relay 32, winding of relay 34, to ground; and the energizing circuit for a 25 relay 35 at substation B being traceable from the same source of current through control wire 10 and including the contacts of polarized relays 22, 24, 26, 29, 31 and 33 at station B over a circuit corresponding to 30 that just traced for relay 34 at station A. The operation of relays 34 and 35 opens the line wire 14 at contacts 45 and 46 and closes contact 75 of relay 34 and contact 76 35 of relay 35, the closing of contact 75 causing positive current to flow to the windings of the uppermost coils of relays 21, 23, 25, 28, 30 and 32 and the closing of contact 76 causing positive current to flow to the windings of the uppermost coils of relays 22, 24, 26, 29, 31 and 33 thus causing all these coils which are polarized negatively to be energized and to repel their armatures and causing them to become disengaged from the upper pole pieces to which they are frozen. The armatures of all these relays thereupon 40 return to the normal position shown in the drawing. Relays 34 and 35 are restored to normal position by the opening of contacts 74 and 77 of relays 32 and 33, respectively, and relays 34 and 35, in deenergizing, open contacts 75 and 76 thus cutting off the current to the upper windings of the polarized 45 relays. The reason for momentarily opening the line wire at contacts 45 and 46 during 50 the restoration of the other relays is to prevent current from flowing from station A to station B, or vice versa when contacts of the various relays corresponding to contact 41 of relay 21 close momentarily during this operation.

It will be seen that by means of this invention the remote control and supervision of switches and other devices is accomplished without the use of selectors, thereby increasing the speed of operation and eliminating motor driven units at the substation, and without the use of start-stop distributors thereby eliminating synchronized machines at the control station and substation. Three 55 units of control and three of supervision only are shown, but a considerable number of additional units can be operated over the same wires, the system being practically unlimited in the number of units that may be controlled and supervised over the same pair of wires. It is therefore not intended to limit the invention to the specific system shown and described except within the scope 60 of the appended claims.

What is claimed is:

1. In combination, a control station, a remote station, a plurality of devices at the remote station to be controlled from the control station, a series of relays at the control station and a corresponding series of relays at the remote station, a conductor connecting the two stations, means for impressing impulses of current on said conductor, means whereby responsive to these impulses the series of relays at both stations operate sequentially and in synchronism, a second conductor connecting the two stations, an operating relay at the remote station for each device thereat to be controlled normally disconnected from said second conductor, a key at the control station for each device to be controlled normally disconnected from the second conductor and associated with a source of current and means whereby said series of relays in their sequential and synchronous operation connect in sequence the operating relays and the corresponding keys to said second conductor. 105
2. In combination, a control station, a remote station, a plurality of devices at the remote station to be controlled from the control station, a series of relays at the control station and a corresponding series of relays at the remote station, a conductor connecting the two stations, means for impressing impulses of current on said conductor, means whereby responsive to these impulses the series of relays at both stations operate sequentially and in synchronism, a second conductor connecting the two stations, an operating relay at the remote station for each device thereat to be controlled normally disconnected from said second conductor, a key at the control station for each device to 110
- 120
- 125
- 130

be controlled normally disconnected from the second conductor, sources of current of different character adapted to be associated with said second conductor by each key, and 5 means whereby said series of relays in their sequential and synchronous operation connect in sequence the operated relays and the corresponding keys to said second conductor.

3. In combination, a control station, a remote station, a plurality of devices at the remote station to be controlled from the control station, a series of relays at the control station and a corresponding series of relays at the remote station, a conductor connecting 10 the two stations, means for impressing impulses of current on said conductor, means whereby responsive to these impulses the series of relays at both stations operate sequentially and in synchronism, a second conductor connecting the two stations, an operating relay at the remote station for each device thereto to be controlled normally disconnected from said second conductor, a key at the control station for each device to be 15 controlled normally disconnected from the second conductor and associated with a source of current, means whereby said series of relays in their sequential and synchronous operation connect in sequence the operating 20 relays and the corresponding keys to said second conductor, a second series of relays at the control station and a second corresponding series of relays at the remote station, means whereby responsive to the impulses 25 30 35

character thereto, a signal controlling relay 40 at the control station for each device normally disconnected from said second conductor, and means whereby said second series of relays in their sequential and synchronous operation connect in sequence the 45 switches and signal control relays to said second conductor.

4. In combination, a control station, a remote station, a plurality of devices at the remote station to be controlled from the control station, a series of polarized relays at the control station and a corresponding series of polarized relays at the remote station, a conductor connecting the two stations, means for impressing positive and negative impulses of current on said conductor, means whereby responsive to these impulses the series of relays at both stations operate sequentially and in synchronism, a second conductor connecting the two stations, a polarized operating relay at the remote station for each device thereto to be controlled normally disconnected from said second conductor, a key at the control station for each device to be controlled normally disconnected from the second conductor, sources of current of positive and negative polarity adapted to be associated with said second conductor by each key, and means whereby said series of relays in their sequential and synchronous operation connect in sequence the operating relays and the corresponding keys to said second conductor. 60 65 70

In witness whereof, I hereunto subscribe my name this 16th day of January, A. D. 75 1922.

FERDINAND ZOGBAUM.
